ATTORNEY

UNITED STATES PATENT OFFICE.

DAVID W. O'BRYAN, OF MOUNT AUBURN, ILLINOIS.

RAIL-SPIKE.

1,214,578.

Specification of Letters Patent. Patented Feb. 6, 1917.

Application filed January 7, 1916. Serial No. 70,854.

To all whom it may concern:

Be it known that I, DAVID W. O'BRYAN, a citizen of the United States, residing at Mount Auburn, in the county of Christian 5 and State of Illinois, have invented certain new and useful Improvements in Rail-Spikes, of which the following is a specification.

This invention relates to rail spikes, and 10 has for its principal object to provide a spike which will lock itself against accidental removal from a tie after it has once been driven therein.

Another object of the invention is to provide 15 a spike which is simple in construction, cheap and easy to manufacture, and which is positive in its locking operation.

With the foregoing and other objects in view the invention consists in the novel 20 features of construction and arrangement of parts as will be hereinafter more fully described, illustrated in the accompanying drawings, and claimed.

In the drawings: Figure 1 is a vertical 25 sectional view through the spike as associated with a tie and rail showing the locking means in operative position; Fig. 2 is a vertical sectional view through the spike, showing the position the locking member 30 assumes when the spike is disengaged from the tie; Fig. 3 is a face view of the spike; Fig. 4 is a view similar to Fig. 2 with the locking member removed.

Referring to the drawings by numerals 35 wherein is illustrated the preferred embodiment of the invention, 1 designates a railroad rail which is adapted to be fastened to the tie 2 by means of the improved spike 3, the said spike 3 being of the ordinary 40 exterior construction and comprising the pointed shank 4 and a head 5.

A recess 6 is formed in the inner face of the shank 4 and extends from a point a short distance below the top of the head 5 45 to a point approximately intermediate the ends of the shank 4. This recess 6, at its lower end extends entirely through the width of the shank 4 and at an angle to itself, as indicated at 7, the walls of the recess at the point 7 being curved upwardly and inwardly toward the inner end of the head 5 for a purpose which will presently appear.

Adapted to be inserted within the recess 6 55 is a locking member 8 which is of slightly less length than the recess 6 and has at its

upper end a head 9 which is arranged within the recess and has a portion thereof projecting beyond the inner face of the shank, as clearly illustrated in Fig. 2 of the 60 drawings. At its lower end this locking member is provided with an offset portion 10 which is adapted to extend through the opening 7 and which has its upper and lower faces shaped to the angular arrangement of the walls of the opening 7, with which it is adapted to be snugly engaged. Formed upon the inner face of the member 8 adjacent the offset portion 10 is a spur 11 which is adapted to bite into the fibers of 70 the tie when the spike is driven home therein.

A pair of alined openings are formed in the side walls of the spike adjacent the inner edge thereof and through these openings is adapted to be passed a pin 12 to prevent the accidental removal of the locking member 8 from within the recess 6, the pin 12 being arranged in spaced relation from the inner face of the member 8 so 80 that inward movement of the said member will be permitted when the spike is driven into the tie.

In operation the pointed end of the spike is positioned adjacent the base flange of the 85 rail and the spike driven home in the ordinary manner. The member 8, however, is of slightly less length than the recess 6 so that in driving the spike into engagement with the rail the head 9 of the member 8 90 will come in contact with the base flange of the rail before the head 5 of the spike proper has been driven into final engagement therewith. Consequently as further driving of the spike takes place to bring 95 the head 5 into engagement with the rail, the angular faces of the offset portion 10 ride against the angular faces of the walls of the opening 7 and force the locking member inwardly, which inward movement will 100 cause the spur 11 to engage with the fibers of the tie and thus securely fasten the spike against accidental removal therefrom.

From the foregoing description taken in connection with the accompanying drawings 105 it is thought that the construction and operation of the improved spike will be clearly understood, and while I have herein shown and described one preferred embodiment of my invention, I do not wish to be limited 110 thereto except for such limitations as the claim may impart.

I claim—

A spike including a shank and a head
extended from one side thereof at the upper
end of the shank, said shank having a
5 longitudinal recess in one side, the lower
end of the recess being curved and extended
through the shank to the opposite side
thereof, the upper end of said recess being
turned in the opposite direction and ex-
10 tended in the bottom of said head, a locking
member including a narrow shank engaged
in said recess and provided with the turned
pointed upper end to be received in the upper
end of said recess, said locking mem-
15 ber having an enlarged lower end provided
with opposite curved faces adapted to nor-
mally engage the curved walls of the lower

turned end of said recess, said locking
member having a pivoted spur formed at
its lower end and extended in a direction 20
opposite to the enlargement of said lower
end, said spur normally resting in the main
straight portion of said recess, and a pin
extended across said recess opposite the nar-
row shank portion of said locking member 25
to limit transverse movement of the latter
within said recess.

In testimony whereof I affix my signature
in presence of two witnesses.

DAVID W. O'BRYAN.
